PLANTER

Gilbert C. Frenz, Milwaukee, Wis.

Application August 20, 1952, Serial No. 21,133

Term of patent 7 years

(Cl. D35—3)

To all whom it may concern:

Be it known, that I, Gilbert C. Frenz, a citizen of the United States, and a resident of Milwaukee, in the county of Milwaukee, and State of Wisconsin, have invented a new, original, and ornamental Design for a Planter, of which the following is a specification, reference being had to the accompanying drawing, forming a part thereof:

Fig. 1 is a front perspective view of a planter showing my new design;

Fig. 2 is a side elevational view thereof.

I claim:

The ornamental design for a planter, substantially as shown.

GILBERT C. FRENZ.
